UNITED STATES PATENT OFFICE

JOHN F. FARMER, OF INDIANAPOLIS, INDIANA

DISPENSING MACHINE

Application filed April 1, 1931. Serial No. 526,800.

This invention relates to the art of dispensing devices and particularly to a structure adapted to dispense articles which may vary in sizes and the price of which articles 5 may also vary, in which case a varying number of the articles may be sold for a single coin.

A primary object of my invention is to provide a structure which may receive and 10 dispense articles in bulk or packaged form without change in the structure.

A primary object of the invention resides in the novel means for receiving and retaining articles to be dispensed and in the control 15 for dispensing a fixed number of such articles upon operation of the device.

Further important objects reside in the new and useful assembly of the various elements permitting the production of a dispensing device at a relatively low cost and permitting an extremely simple operation thereof.

These and other objects will become apparent in the following description of the 25 invention as illustrated in one particular form in the accompanying drawings, in which

Fig. 1 is a front elevation of a display case in which my invention is embodied;

Fig. 2, a vertical transverse section on the line 2—2 in Fig. 1 on an enlarged scale;

Fig. 3, a vertical longitudinal section on the line 3—3 in Fig. 2;

Fig. 4, a detail in fragmentary top plan 35 view of the control mechanism; and

Fig. 5, a longitudinal vertical section on the line 5—5 in Fig. 4.

Like characters of reference indicate like parts throughout the several views in the 40 drawings.

Within a show case 10, in the upper part thereof, I fix a horizontally disposed shaft 11 on which are rotatably carried a number of spiders 12. Each spider has one end of a torsional spring 13 fixed thereto which is wrapped about the shaft to have the other 45 end secured by a collar 14 fixed to the shaft 11 by the set screw 15, the end of the spring being engaged about the screw.

Each spider 12 has a plurality of stirrups

16 attached thereto extending radially from the spider to have their planes include the axis of the shaft 11. Each of the stirrups 16 carries a bucket 17 suspended by brackets 18 and 19 each of which is rotatably mounted on the stirrup to support the bucket 17 therebetween, Fig. 3. The brackets 18 and 19 have inturned tongues 20 to extend under the bracket and forwardly extending ears, Fig. 2, through which ears rivets 22 are passed into the bucket 17 to rotatably secure the bucket 17 whereby the rear portion of the bucket normally rests on the tongue 20 and the forward portion is supported by the rivets.

Each stirrup 16 has a pin 23 projecting laterally from one side, each pin being adapted to contact consecutively with the under side of the intercepting plunger 24. The plunger 24, Figs. 4 and 5, comprises a slide bar 25 slidably guided within the sleeve 26 and a rear stop 27 which is fixed to the slide 70 bar 25 and has a horizontally disposed lip 28 with an opening 29 cut therethrough at a distance from the rear end of a sufficient width to permit the pins 23 to pass upwardly therethrough.

A spring 30 fixed to an ear 31 and to the wall of the case 10 normally holds the plunger 24 in an outward position, Fig. 2, whereby a pin 23 may contact the lip 28 back of the opening 29. The sleeve 26 extends through the wall of the case 10 and a push button 32 is secured on the outer end of a slide bar 33 which is slidably guided within the sleeve 26, Figs. 4 and 5, the slide bar 25 and the bar 33 being notched on their vertically opposed faces so as to permit a coin 34 to be inserted through an opening on the top side of the sleeve 26 between the two bars in such a manner that the shoulder of the notch on the bar 33 will press against the coin 34 so as to carry it against the opposing shoulder on the bar 25, all in such a manner that by pushing inwardly on the button 32 with a coin inserted as described the bar 25 will be carried rearwardly by the intervening coin. A trough 35 is fixed to the underside of the sleeve 26 to receive the coin 34 through an opening in the sleeve rearwardly disposed in relation to the 100

top opening in the sleeve and extends rearwardly within the case 10 to any suitable location such as above a coin receiving box 36, Fig. 2. The shoulders on the bars 26 and 33 are relieved from their undersides so that when the coin 34 has been pushed to the rear by pressure on the button 32 sufficiently, the coin 34 may drop by gravity into the trough 35.

10 In operating the device, the upper door 37 of the case 10 is opened to permit access to the buckets 17 which may be filled with the articles to be dispensed. As each bucket is filled it is pushed downwardly from the door 37 in a clockwise direction, Fig. 2, in order to bring the next above bucket therearound for filling.

15 In this filling operation the pins 23 strike on the upper side of the lip 28. The stop 27 is rockably secured to the slide bar 25 by the pintle 38 and is normally held in a horizontally disposed position by the pull of the spring 30. However as the pins 23 consecutively strike the lip 28, the stop 27 is rocked 20 downwardly to permit the pins 23 to pass downwardly therebelow. The projecting ears of the stop 27 through which the pintle 38 passes serve as a stop to bear against the rear end of the sleeve 26 to limit the forward travel of the stop 27 and bar 25 under the pull of the spring 30.

25 After all of the buckets 17 have been filled as desired, the door 37 is closed and the device is ready to be operated by the insertion 30 of the coin 34 in the opening in the top side of the sleeve 26, following which the button 32 is pressed inwardly. The buckets being pushed downwardly in the filling operation are moved to cause the spring 13 to become 35 wound tightly about the shaft 11 in such a manner that the buckets tend to be moved in a counter-clockwise direction through the tendency of the spring 13 to unwind and carry the spider 12 around about the shaft 40 11. This reverse travel, however, is prevented by reason of the pin 23 being pressed upwardly against the underside of the lip 28 after the pin has been pressed downwardly 45 sufficiently to have rocked the stop 27 and 50 passed thereunder.

Now as the button 32 is pressed inwardly with the coin having been inserted as above described, the stop 27 is likewise pushed inwardly against the pull of the spring 30 sufficiently 55 to bring the opening 29 over the pin 23 so as to permit that pin 23 to be carried through the opening 29 under the pull of the spring 13 to cause that pin to strike against the underside of the upper overturned lip 39 projecting horizontally from the side wall of the stop 27, Fig. 5.

60 As the pin 23 passes through the opening 29, the coin 34 drops into the trough 35 and thereby permits the spring 30 to return the stop 27 forwardly against the sleeve 26. On

the forward side of each bucket 17 is an upturned hook 41 and a bar 42 is positioned in the path of these hooks whereby as the pin 23 travels through the opening 29 in the stop 27, the hook 41 engages the bar 42 and, 70 as the pin travels upwardly, the stirrup 16 pulls the brackets 18 and 19 upwardly to cause the bucket 17 to rock about the pivot rivets 20 and thereby dump the contents of the bucket out through an opening through 75 the forward side of the case 10 which is covered by a hood 43 directing the contents so dumped downwardly onto a platform 44 running across the length of the case 10.

80 This operation may be repeated as many times as there are buckets 17 until the last bucket has been unloaded at which time a finger 45 fixed to the stirrup 16' comes around and strikes the underside of the stop 27 so as to prevent further travel of the spider 12. A shoulder 46 on the arm 45 then extends upwardly behind the stop 27 whereby the stop 27 cannot be pushed rearwardly even though a coin be inserted within the sleeve 26 in the usual manner. In this position the button 32 cannot be pushed inwardly and the coin remains stationary and can be withdrawn from the sleeve.

85 As indicated in Fig. 1 any number of dispensing units may be embodied in one case, seven such units being here indicated with varying sizes of hoods 43 to permit the discharge of varying sizes of articles and quantities thereof. The opening into the sleeve 26 may be varied to receive different sizes 90 of coins depending upon the articles to be dispensed. The front portion 38 of the case 10 will preferably be of glass to enable the purchaser to see the contents of the buckets when making selections for his purchase.

100 While I have here shown and described my invention in the one best form as now known to me, it is obvious that structural changes may be made without departing 105 from the spirit of the invention and I, therefore, do not desire to be limited to that precise form nor any more than may be required by the following claims.

110 I claim:

115 1. In a coin controlled merchandise vending device, a rotatable reel, means for separately and automatically rotating the reel in one direction, an annular series of merchandise containing buckets supported by the reel, a push bar arresting the automatic movement of the reel in the outer position of the bar and releasing it at the inner position of the bar, said bar having an inner end with a passage having pin-arresting offsets through 120 which the pins successively pass, said end being jointed to swing in one direction only for the manual reverse movement of the reel in the operation of filling the buckets.

125 2. In a coin controlled merchandise vending device, a rotatable reel, a spring for the 130

- reel separately and automatically rotating it clockwise, an annular series of merchandise containing buckets supported by the reel, a push bar arresting the automatic movement of the reel in the outer position of the bar and releasing it at the inner position of the bar, said bar having an end with a passage having pin-arresting offsets through which the pins successively pass, said end being jointed to swing in one direction only permitting the manual movement of the reel counter clockwise in filling the buckets.
3. In a coin controlled merchandise vending device, a rotatable reel, a spring for the reel separately and automatically rotating it clockwise, an annular series of merchandise containing buckets supported by the reel, a push bar arresting the automatic movement of the reel in the outer position of the bar and releasing it at the inner position of the bar, said bar having an end with a passage having pin-arresting offsets through which the pins successively pass, said end being jointed to swing in one direction only permitting the manual movement of the reel counter clockwise in filling the buckets, a trough and means comprising a hook on the bucket and a fixed hook-engaging means for dumping the contents of the buckets seriatim into the trough.
4. In a merchandise vending device, a rotatable reel, means for intermittently rotating the reel, an annular series of merchandise containing buckets swingingly supported by the reel, each bucket having a hook, a trough adjacent the path of the buckets and a member in the path of the hooks near the trough to engage the hook as a bucket passes the trough and dump the bucket contents into the trough.
5. In a merchandise vending device, a rotatable reel comprising an annular series of stirrups, means for intermittently rotating the reel, a pair of brackets pivoted to the stirrup having inturned ends and extensions laterally in the same direction, a merchandise containing bucket between each pair of brackets supported on the inturned ends and pivotally secured to the ends of the lateral extensions, a hook on each bucket, a trough, and a hook engaging member near the trough in the path of the hooks to engage each hook as it passes and dump the contents of the bucket into the trough.
6. In a merchandise vending device, a rotatable reel comprising an annular series of stirrups, means for intermittently rotating the reel, a pair of brackets pivoted to each stirrup having inturned ends and extensions laterally in the same direction, a merchandise containing bucket between each pair of brackets supported on the inturned ends and pivotally secured to the ends of the lateral extensions, a hook on each bucket, a trough, and a hook engaging member near the trough in the path of the hooks to engage each hook as it passes and dump the contents of the bucket into the trough.
7. In a coin controlled merchandise vending device, one or more rotatable reels, spring means for rotating each reel in a clockwise direction, an annular series of merchandise containing buckets swingingly supported by each reel, a pin laterally projected from each bucket, a push bar for each reel having a bottom normally crossing the path of the pins in its outermost position to arrest the reel, a spring to hold the bar in this normal position, said bar having a slot for the passage of the pin when the bar is pushed in and a top to arrest and hold the pin until the bar is returned by the spring to contact the next pin by the bottom of the bar.
8. In a coin controlled merchandise vending device, one or more rotatable reels, spring means for rotating each reel in a clockwise direction, an annular series of merchandise containing buckets swingingly supported by each reel, a pin laterally projected from each bucket, a push bar for each reel normally crossing the path of the pins in its outermost position to arrest the reel, a spring to hold the bar in this normal position, said bar having a separate end hinged to swing only in a downward direction to which end the second spring is attached to also hold up the separate end, said separate end having a slot for the passage of the pin when the bar is pushed in.
- In testimony whereof I affix my signature. JOHN F. FARMER.
